HOLDER FOR RETAINING A PLURALITY OF PANELS AT THE CORNERS THEREOF

James J. Westgerdes, Fort Recovery, Ohio, assignor to
Premiere Corporation, Dayton, Ohio

Filed July 30, 1973, Ser. No. 383,522

Term of patent 14 years

Int. Cl. D9—99

U.S. Cl. D9—293

FIG-1

FIG-2

FIG-3

FIG-4

FIG. 1 is a front perspective view of a holder for retaining a plurality of panels at the corners thereof showing my new design;

FIG. 2 is a front elevational view;

FIG. 3 is a top plan view;

FIG. 4 is an end view, looking in the direction of the arrows 4-4;

FIG. 5 is a rear elevational view;

FIG. 6 is an enlarged sectional view taken substantially on line 6-6 of FIG. 5;

FIG. 7 is an enlarged sectional view taken substantially on line 7-7 of FIG. 5;

FIG. 8 is an enlarged sectional view taken substantially on line 8-8 of FIG. 5; and

FIG. 9 is a view similar to FIG. 1, showing a modified form of my new design wherein only the front has been modified as shown.

I claim:

The ornamental design for a holder for retaining a plurality of panels at the corners thereof, as shown and described.
